UTILITY PRESS

Newman M. Marsilius, Trumbull, Conn.

Application November 27, 1945, Serial No. 631,081

4 Claims. (Cl. 164—101)

1

This invention relates to new and useful improvements in presses and has particular relation to a press of general utility in machine shops, manufacturing establishments, etc.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a side elevational view of the upper portion of the press of the invention only the supporting legs or structure for the bed being omitted;

Fig. 2 is a view partly in section and partly in side elevation to show details of construction;

Fig. 3 is a top plan view of the entire press;

Fig. 4 is an enlarged side elevational view of a portion of the head showing a locking plunger and some associated parts;

Fig. 5 is an enlarged side elevational view taken as along the plane of the line 5—5 of Fig. 2; and

Fig. 6 is a detailed sectional view taken as along the line 6—6 of Fig. 2.

The present invention has many uses, such as for shearing punches and dies in a tool room, for separating punches and die holders, for assembling and aligning punches and dies, for use as a straightening press, and for use as an arbor press. Thus, it will be seen that the press is of rather general use and constitutes quite an asset in any tool room, although for some purposes it may be used in actual production work.

Referring in detail to the drawings, the press of the invention is shown as including a bed 10 which may be formed with or attached to any suitable base or supporting legs or the like. Disposed over the bed 10 is a yoke-like structure generally designated 11 and shown as somewhat in the shape of an inverted Y including legs 12 and 13 straddling the intermediate portion of the bed 10 and a hollow upstanding portion 14 including an enlarged or head-like portion 15 at its upper end.

By means of bolts or the like 16, the yoke structure 11 is secured to the bed 10, these bolts being shown as passing through foot portions 17 on the arms 12 and 13 and then entirely through the bed 10. In its upper surface the bed may be provided with any desired number of tapped holes

2

or recesses 18 for the reception of bolts when clamping work to the bed. The yoke-like member 11 may include strengthening ribs 19, as shown.

Within the upright portion 14 there is fixed a sleeve 20 vertically disposed and extending from a position within the head 15 through to the lower end of the upright 14 and attached to such lower end as by means of screws 21. Within this sleeve is a bar 22 having a keyway 23 extending for substantially its entire length. A key 24 inserted through a hole in the sleeve 20 enters the keyway 23 and thus holds the bar 22 against turning movement in the sleeve 20 but permits movement of such bar longitudinally of the sleeve.

Located within the hollow head 15 is a worm gear 25 with which meshes a worm 26 fixed on a shaft 27 extending to the outer side of the machine and there mounting a relatively large diameter hand wheel 28. Threaded through the worm gear 25 is a jackscrew 29 at its lower end reduced (see Fig. 6) to provide a neck 30 and at the free end of such neck having an integral head-like portion 31. This head-like portion occupies a recess in the upper end of the bar 22 and the neck-like portion 30 of the jackscrew is located in the inner end portion of a laterally opening slot 32 in such upper end portion of the bar 22. With this connection between the bar and the jackscrew, it will be apparent that such parts are adapted for relative turning movement and that they are connected for endwise movements together.

The screw 29 has a longitudinally extending keyway 33 and at the upper side of the head 15 this screw passes through a bushing 34 carrying a key 35 located in the keyway 33 of the jackscrew. At its lower end, bushing 34 includes a radial flange 36 located against the upper side of the head 15 and held against movement away from such head by means of a clamping ring 37 secured in place by screws 38.

About the bushing 34 and secured thereto by key 39 is a relatively large hub-like portion 40 of a large hand wheel, generally designated 41. This hand wheel is horizontally disposed and of a diameter extending outwardly over the vertically disposed hand wheel 28. Hand wheel 41, at its underside and radially with respect to the hub portion 40, is provided with web-like portions 42 and 43, each having a socket 44 opening through its lower end.

On one side of the head 15 there is formed or mounted a relatively thick plate-like member 45

having a vertically extending cylindrical opening 46 therethrough and an elongated side opening 47. Within the opening 46 there is mounted a bolt 48 to which is secured a pin or handle 49 passing outwardly through the opening 47. In one side, the bolt 48 has a pair of notches 50 and 51 and a coil spring 52 constantly urges a small ball 53 toward the bolt 48 so as to have such ball snap into either the recess 51 or the recess 50, whichever may be presented opposite the ball.

A small plug 54 may be used for securing the spring 48 in place. The bolt 48 is so located that when the wheel 41 is turned to present one of the sockets 44 above the bolt, the latter may be manually shifted to dispose its upper end in such socket. This is as shown in Figs. 4 and 5 and the bolt will be manually shifted through the manipulation of the pin 49. When the bolt is in locking relation with the wheel 41, ball 53 is held in the notch 51 and maintains the bolt elevated against casual displacement. When the bolt is pulled down into an inoperative position, the ball 53 may snap into the notch 50.

Fixed to the lower end of the bar 22 is a shank holder, generally designated 55, and comprising a shank portion 56 fixed to the bar 22 and a block 57. A corresponding block 58 is adapted to be clamped in place by means of bolts 59. When the block 58 is tight in place, it together with the block portion 57 may be clamping any shank 60 of a punch block 61 comprising part of the die set, generally designated 62 in Fig. 1.

When using the press of the invention any work may be mounted on the bed 10. For example, in Fig. 1 the dotted lines suggest positioning of a die set on the bed. This die set may not have been in use for some time and to separate the blocks considerable force will be needed. Therefore, when it is properly aligned with the shank holder and clamped to the bed 10 the shank holder is clamped tight to the shank 60 of the punch block. Now by operating either of the wheels, 28 or 41, the punch block is drawn upwardly on the pins of the die set as to the position shown.

Wheel 41 is used for rapidly moving the bar 22 upwardly and downwardly, depending on the direction in which the wheel is turned. At such time the lock bolt 48 is in its lower position free of the sockets 44. As wheel 41 is turned the worm wheel 25 functions as a nut and the screw 29 is fed through the gears. This is true since worm 26 will prevent turning of the worm wheel and the latter cannot move laterally or along the screw being held between the upper end of sleeve 20 and the upper wall of the head 15.

The immediate result of turning wheel 41 is to turn the hub 40 and through the key 39 the bushing 34. Through key 35 the said bushing is secured to the jackscrew for turning of the latter. As the screw turns it is fed longitudinally and raises or lowers the bar 22 and thus the shank holder 55, or any other means attached to the bar. The latter being held by key 24 has no turning movement in the fixed guide sleeve 20.

Movement of screw 29 and bar 22 through manipulation of the hand wheel 28 is at a much less rate for a given movement of such wheel than when the wheel 41 is used. When wheel 28 is rotated the lock bolt 48 is in one of the sockets 44 so that wheel 41 is held against turning movement and since such wheel is keyed to the screw 29, the latter may not rotate but may be fed longitudinally. Wheel 28 turns the worm 26 and through the latter the gear 25. Such gear is held

against all but turning movement and therefore when rotated, acts as a nut to feed the jack screw 29, which is being held against all but longitudinal movement. The ratio in the gearing shown is such that for one revolution of the wheel 28 the screw is moved one thirty-second of an inch.

From this it will be apparent that wheel 28 may be used to exert a tremendous pressure through the bar 22. In using the press of the invention, wheel 41 may be rapidly rotated to shift the bar to a position where great pressure is to be exerted. In fact, the wheel 41 may jamb the bar against a piece of work. Thereafter wheel 41 is secured by lock bolt 48 and the wheel 28 turned to apply the required pressure. It is noted that while both wheels are of relatively large diameters, the wheel 41 extends out over and beyond the wheel 28.

Having thus set forth the nature of my invention, what I claim is:

1. In a press, a bed, a yoke-like frame having its arms secured to opposite edge portions of said bed, said frame including an intermediate vertically extending hollow portion having a head at its upper end, a bar vertically movable in said vertically extending portion, a screw connected to said bar but rotatable relative thereto and extending to the upper side of said head, a hand wheel about the upper end portion of said screw above said head, and comprising a hub, a bushing within and keyed to said hub, means securing said bushing to said frame head but for turning movement relative thereto, a key and keyway connecting said bushing and said screw, a worm wheel threaded to said screw within said head, a worm meshing with said worm gear, a hand wheel for turning said worm, and means holding said worm wheel against any but turning movement in said head.

2. A press as in claim 1 wherein the second mentioned hand wheel is vertically disposed and the first mentioned hand wheel is horizontally disposed and extends radially outwardly over the second mentioned hand wheel.

3. A press as in claim 1 wherein said first mentioned hand wheel is horizontally disposed, means providing downwardly facing sockets on said first mentioned hand wheel, and a vertically slidable lock bolt on said frame and adapted to be moved into one of said sockets to secure said first mentioned hand wheel and thereby said screw against turning movement when the second mentioned hand wheel is being turned.

4. A press as in claim 1 wherein said screw toward its lower end has a reduced diameter neck-like portion inwardly of its lower end and an integral head-like portion below said neck-like portion, and said bar has a recess in its upper end portion rotatably receiving said head-like portion of the screw and a laterally opening slot from said recess through its upper end receiving the neck-like portion of the screw whereby the screw and bar may rotate relatively but must move longitudinally together.

NEWMAN M. MARSILIUS.
